Inventor:

Justus A. Traut,
By his Attorney,

J. A. Richards.

UNITED STATES PATENT OFFICE.

JUSTUS A. TRAUT, OF NEW BRITAIN, CONNECTICUT.

SUSPENDER-BUCKLE.

SPECIFICATION forming part of Letters Patent No. 446,543, dated February 17, 1891.

Application filed September 20, 1890. Serial No. 365,604. (No model.)

To all whom it may concern:

Be it known that I, JUSTUS A. TRAUT, a citizen of the United States, residing at New Britain, in the county of Hartford and State 5 of Connecticut, have invented certain new and useful Improvements in Buckles for Suspenders, of which the following is a specification.

This invention relates to buckles for suspenders and to that class of said buckles having cast-offs, the object being to provide a buckle of that class which shall be simple in construction, cheaply manufactured, and have effective locking devices.

15 In the drawings accompanying and forming a part of this specification, Figure 1 is a front view of a buckle embodying my present improvements. Fig. 2 is an edge view of the complete buckle shown in Fig. 1. Fig. 3 is a 20 transverse sectional view through the middle of the buckle. Fig. 4 is a front view of the web-cases. Fig. 5 is a front view of the lever-plate and is illustrative of the mode of assembling the parts. Fig. 6 is a front view 25 of the slide. Fig. 7 is a cross-sectional view of the slide on the line *a a*, Fig. 6. Fig. 8 is a front view showing a modification of the web-case. Fig. 9 is a front view of a lever-plate prepared for insertion in the modified web-case. Fig. 10 is a plan view of the lower end 30 of the lever-plate shown in Fig. 5. Fig. 11 is a plan view of the lever-plate blank.

Similar characters designate like parts in all the figures.

35 My improved buckle consists of a frame or web-case, a lever or lever-plate, and a slide. The frame or web-case *C* is of the nature of a short tube having a front plate 2, a back plate 4, and two ends 3 and 5, connecting said front and 40 back plates. In the front plate of the frame is formed a slot 7, wherein is pivotally supported the lever-plate *L*, which is provided with suitable teeth 15 for engaging the web of the suspender (not herein shown) in a well-known manner. The lever-plate is shown in 45 blank form in Fig. 11, and is bent on the lines *ff*, *ee*, and *dd*, as best shown at 9 in Figs. 2 and 3. Said lever has notches on either side thereof at 16 and 18, which engage with the 50 front plate 2 at the ends of the slot 7, as will be understood by comparison of Figs. 1, 2, and 5. The inwardly-projecting end 12 of the lever-plate *L* should be, at least in part, malleable, and is extended sidewise to form

the ears 11 and 13, which engage the front 55 plate 2 on the inner side thereof. As a means for assembling the frame or web-case and lever, said case has a lateral or branch slot or notch 10 at one end of the pivot-slot 7. The lever-plate is prepared for insertion in said pivot-slot by having the malleable ear 13 bent, as 60 shown in Fig. 5, to a position corresponding to said notch 10. This will be understood by comparison of Figs. 4 and 5. The lever-plate being thus prepared, it is taken in hand by the 65 operator and the end 12 thereof inserted into said slot 7, when the ear 11 is slid under the top plate 2 at the left-hand end of the slot in Fig. 4. Next the bended ear 13 is slipped down through the notch 10 and afterward 70 straightened to the position indicated by dotted lines at 13 in Figs. 1 and 5, so that said ear 13 then lies behind the front plate at the right-hand end of the pivot-slot 7, as shown by dotted lines at 13 in Fig. 1. The 75 notch 10 being formed in a downward direction from the pivot-slot 7 is wholly covered by the lever-plate, (this being suitably shaped therefor,) as will be understood from Fig. 1, thus giving a neat and symmetrical 80 appearance to the buckle. This method of constructing and assembling the front plate and the lever-plate has important operational and economic advantages, since the working fit of these parts is determined by the 85 cutting-out punches and is not dependent on the accurate assembling of a composite frame, as in many of the old kinds of buckles. In some cases, however, the lateral notch 10 may be extended upward from the pivot-slots 90 7, as indicated, for instance, at 10' in Fig. 8; also, a similar branch slot may be provided at each end of said pivot-slot, as indicated in said Fig. 8, where the second branch slot is designated by 10''. When this arrangement 95 is used, however, the lever-plate is prepared for assembling by bending the ear 13, as shown in Fig. 9. When two branch slots are used, as shown in Fig. 8, it is immaterial which of the ears 11 or 13 is bent, as described. 100

The lever-plate, which is formed without the usual "box," is, for the purpose of attaching the slide thereto, slotted and bent, substantially as shown, so as to receive and hold the slide in a way that is at once rigid and 105 secure. The lower end of the lever-plate is bent backward, and it may be upward, as shown in Figs. 1 and 2, to form the guard 19

back of the slide. In the front of the lever-plate there are two slots 25 and 26, having between them the guide-bar 27 and connecting with the mortise or slot at 28, (see Figs. 3 5 and 10,) which is in the lower end of the lever-plate. This mortise (shown in inverted plan view in Fig. 10) is of a size suitable for receiving the detachable slide B, and has projecting thereinto the catches 30 and 32 for engaging the slide or "cast-off."

The slide consists of the slide-plate 31, having a loop, as 32, or other means for attaching thereto the suspender-straps. Said slide-plate has thereon the spring 34, which has a transverse cut, as 35, formed therein, the middle part of the spring-plate below said cut being swaged forward, as indicated in Figs. 6 and 7, to form the space or box 36, Fig. 7, for receiving the aforesaid guide-bar 27 of the lever-plate, as shown in Figs. 2 and 3. The function of said guide-bar is to guide the slide to place, and then to hold in place the upper end thereof against any displacement laterally or toward the back of the buckle-plate. When the slide is in place, the edges of the box 36 (which is formed, as described, on the spring 34 of the slide) lie in the aforesaid slots 25 and 26, so that the edges of the plate at the sides of said slots constitute guides to prevent lateral or sidewise play of the slide in the lever-plate. The box part or "ease" 36 of the said spring then lies forward of the guide-bar 27, as clearly shown in Figs. 1, 2, and 3, while the side portions of said spring lie behind the lever-plate, as indicated by dotted lines in Fig. 1. When the slide is slid into place through the aforesaid mortise 28, the lower corners of the spring form hooks, which rest upon the catches 30 and 32 of the lever-plate, and thus lock the slide in place, as shown in Fig. 3. In using the cast-off the user grasps the suspender and presses on the outer surface of the box 36 as on a bush-button, thereby closing the spring 45 and disengaging the same from the aforesaid catches 30 and 32, when the slide may be readily withdrawn.

The improved blank for a buckle-plate shown in Fig. 11 constitutes subject-matter 50 for a separate application.

Having thus described my invention, I claim—

1. In a buckle, the combination, with the frame, of the lever-plate pivotally supported 55 in the frame and having in the rearwardly-bent lower end thereof a slide-receiving opening, catches on the lever-plate at said opening, guide-slots in the lever-plate extending to said opening, and a spring-provided slide 60 formed to enter said opening and guide-slots and engage said catches.

2. In a buckle, the combination, with a frame or web-case having the continuous transverse pivot-slot to receive the lever and 65 having at one end of said slot a lateral notch substantially at right angles thereto, of the lever having the pivot-notches in the edges

thereof and bent on the line of said notches to form the inwardly-projecting end, said inwardly-projecting end being extended to 70 form ears adapted for engaging under the frame at the ends of said slot, one of said ears being malleable and adapted to be bent, as set forth, for insertion through said notch, whereby the frame and lever may be assembled. 75

3. In a buckle, the combination, with the frame having the continuous transverse pivot-slot and having a notch substantially at right angles thereto at one side of one end 80 of said slot, of the lever having the notches 16 and 18 and the projecting ears 11 and 13 on the inwardly-projecting end of said lever, one of said ears being adapted to be bent for insertion through said notch and afterward 85 straightened to its original and working position, whereby the lever may be placed in working position by the bending of only one of said ears.

4. In a buckle, the combination, with a buckle-plate bent backward at its lower end and having therein a slide-receiving opening joining guide-slots formed in the plate on either side of a guide-bar, of a guide-bar and a slide-plate having the middle part 95 thereof forward of its side parts, whereby on sliding said slide-plate into place said middle part comes forward of the guide-bar, while said side parts pass back of the buckle-plate, the slide-plate being guided to place 100 by sliding in said slots, substantially as described.

5. In a buckle, the combination, with the buckle-plate having the slide-receiving opening and the catches, and having guide-slots 105 extending upward from said opening, and having between them a guide-bar, of the two-leaved spring-slide having in one leaf thereof a transverse slot and below the slot shaped to form a box for engaging the guide-bar. 110

6. In a buckle, the combination, substantially as described, with the frame and with the two-leaved spring-slide, of the lever-plate pivotally connected to the frame and slotted, substantially as described, said plate being 115 bent, as set forth, on the lines *e e* and *d d*, and having the guiding-edges, the slide-engaging catches, and the upwardly-extending guard back of the slide.

7. In a buckle, the combination, with the strap-carrying slide having the spring thereof slotted at 35 and the part below said slot thrown forward, as set forth, of the lever-plate having the slide-receiving opening, the guide-slots formed in the plate above the 125 opening, and the slide-engaging catches at the lower end of the guide-slots, said spring part below said slot 35 constituting a push-button for disengaging the spring from the catches, substantially as described.

JUSTUS A. TRAUT.
